(57) **CLAIM**

The ornamental design for a golf tee, as shown and described.

DESCRIPTION

FIG. 1 is a perspective view of the golf tee;
FIG. 2 is a front elevational view of the golf tee, in which the opposing rear elevational view, the right side elevational view, and the left side elevational view are identical to the front elevational view shown;
FIG. 3 is a top view of the golf tee in which the central circle represents a hemispherical concave; and,
FIG. 4 is a bottom view of the golf tee.
